United States Patent Office.

JAMES A. BRADLEY AND FOSTER N. SMITH, OF NEW YORK, N. Y.

Design No. 8,002, dated April 21, 1868.

DESIGN FOR THE ORNAMENTATION OF A HORSE-BRUSH.

The Schedule referred to in these Letters Patent and making part of the same.

TO ALL WHOM IT MAY CONCERN:

Be it known that we, JAMES A. BRADLEY and FOSTER N. SMITH, of the city, county, and State of New York, have invented a new and improved Design for the Ornamentation of a Horse-Brush; and we do hereby declare that the following is a full, clear, and exact description thereof, which will enable others skilled in the art to make and use the same, reference being had to the accompanying drawings, forming part of this specification, in which—

Figure 1 represents a plan or top view of our improved horse-brush.

Figure 2 is an end view of the same.

Similar letters of reference indicate corresponding parts.

This invention relates to the ornamentation of a horse-brush, back and handle, and is fully shown in fig. 1.

The back, A, which is of oval or other shape, has a raised moulding, a, arranged around the low-relief figure, b, of a horse, while the words "Bonner's Dexter" are printed or otherwise formed upon the back, as shown in fig. 1.

The face of the handle B is ornamented, as shown. Two figures, c and d, are arranged around a central oval projection, e, on the handle. Of the two figures c d, one is composed of a series of projecting curves, and the other of a series of re-entrant curves, and both are interlocked in the manner shown.

The ends of the handles are ornamented with foliage, f, and curved lines, g, as shown.

The ornaments are either printed on the handle or are brought out in relief on the same, as shown.

Having described our invention, we claim as new, and desire to secure by Letters Patent—

The design for the ornamentation of horse-brushes, as herein shown and described.

JAMES A. BRADLEY,
FOSTER N. SMITH.
